UNITED STATES PATENT OFFICE.

ADOLF BELER, OF PITTSBURGH, PENNSYLVANIA

FLUID-HEATER.

1,212,732.

Specification of Letters Patent. Patented Jan. 16, 1917.

Application filed November 12, 1915. Serial No. 61,130.

To all whom it may concern:

Be it known that I, ADOLF BELER, a citizen of the United States, residing at Pittsburgh, in the county of Allegheny and State 5 of Pennsylvania, have invented a new and useful Fluid-Heater, of which the following is a specification.

This invention relates to fluid heaters, such as of the instantaneous type, one of the 10 objects being to provide a heater utilizing a plurality of coils all of the coils being connected at one end to a common receptacle and at the other end to a common receptacle, whereby a rapid and complete circulation of fluid through each coil is set up 15 independently of the circulation through the other coils, this action resulting in a quicker heating of the fluid contents of the coils than would otherwise be possible and 20 materially increasing the capacity of the heater.

A further object is to connect the coils to receptacles or headers so located that practically all of the heat generated at the 25 burner will be utilized in raising the temperature of the contents of the coils and receptacles.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed, can be made within the scope of what is claimed, without departing from the spirit of the invention.

In the accompanying drawings the preferred forms of the invention have been 40 shown.

In said drawings:—Figure 1 is a front elevation of a heater embodying the present improvements, parts of the casing being broken away. Fig. 2 is a section on line *a*—*b* Fig. 1. Fig. 3 is a section on line *c*—*d* Fig. 1. Fig. 4 is a front elevation of a modified form of heater, a part of the casing being removed. Fig. 5 is a section on line *e*—*f* Fig. 4. Fig. 6 is a section on line *g*—*h* Fig. 4.

Referring to the figures by characters of reference H designates a heater casing and arranged within this casing is a shallow drum or header 1 having a plurality of 55 openings 2 for the passage of products of combustion. On this header, which is lo-

cated in the upper portion of the casing H may be arranged a thermostat indicated generally at T for controlling the flow of fuel through a fuel conduit C. This thermostat and the mechanism controlled thereby does not constitute any part of the invention and has not, therefore, been shown or described in detail.

Arranged in the lower portion of the casing H is a ring-like header or receptacle 3. A fluid conduit 4 opens into this receptacle 3 while another fluid conduit 5 opens into the receptacle or header 1. Interposed between the two receptacles 1 and 3 is a circular series of coils 6. These coils are arranged in pairs, as shown particularly in Fig. 1, the coils of each pair being oppositely disposed so that the convolutions of the two coils will interfit. The lower convolutions of the coils of each pair are connected to the opposite ends of a T-fitting 7 mounted on and communicating with the receptacle 3. The said coils are similarly connected by T-fittings 8 to the upper receptacle or header 1. Thus fluid flowing from the receptacle 3 into one of the T-fittings 7 will be divided into two streams flowing upwardly through the separate coils connected to the fittings and thence will 85 enter the fitting 8 at the upper ends of the coils and flow into the header or receptacle 1.

In order that the space between the circular series of coils may be partly filled with additional coils, a pipe 9 is extended inwardly from the receptacle 3 to a T-fitting 10 which is supported thereby at the center of the space surrounded by receptacle 3. This T-fitting has separate opposed coils 11 connected to it and extending upwardly to a similar fitting 12 connected to the middle portion of the bottom of the header or receptacle 1. Thus, as shown particularly by dotted lines in Fig. 2, the space within the casing 7 will be almost entirely filled with coils so that it becomes almost impossible for any of the hot products of combustion to leave the casing without coming into contact with some portions of the coils, with the 100 walls of the lower receptacle 3, or with the bottom of the header or receptacle 1. As a result, the greater percentage of the heat will be utilized and better results will be obtained from the burning of a predetermined amount of fuel, than would otherwise be possible. As all of the coils open into com-

mon receptacles at the top and bottom of the casing H, fluid will be drawn equally from all of the coils and the capacity of the heater will be materially increased.

- 5 Instead of providing separate receptacles into which the ends of the coils open, a continuous water jacket 13 can be fitted snugly within the casing H and T-fittings 14 can be arranged within the water jacket at the 10 ends thereof, the ends of the coils being attached to these fittings. Furthermore the pipes 15 can be extended inwardly from the ends of the jacket to the center of the space surrounded by said jacket and can be provided with fittings 16 to which the central coils 17 are attached. With this arrangement of parts, all of the fluid heated within the coils is taken from and discharged into the jacket 13 and the fluid fed to the heater 15 20 is directed first into the jacket and is then withdrawn from the jacket. Consequently an ample supply of heated fluid is accessible at all times and this fluid will be drawn equally from all of the coils. In the forms 25 shown in Figs. 1 to 3 inclusive, it will be seen that the upper receptacle or header 1 constitutes a baffle whereby the greater percentage of heat passing above the coils 11 is absorbed by the contents of the header or 30 receptacle 1.

What is claimed is:—

1. A fluid heater including a ring-like fluid receptacle, a circular series of coils in communication with said receptacle, said 25 coils being disposed in pairs, the coils of each pair interfitting, centrally disposed coils surrounded by said series of coils and communicating with the receptacle, all of the coils overhanging the opening surrounded by the receptacle.
2. A fluid heater including a ring-like fluid receptacle having a space therethrough 40

for the passage of hot products of combustion, a circular series of coils connected to the receptacle, said coils being arranged in 45 pairs, the coils of each pair interfitting, a coil supported at the center of the space surrounded by the receptacle and communicating with the receptacle, and means for directing fluid to and from the receptacle and coils. 50

3. A fluid heater including a fluid receptacle having a space extending therethrough for the passage of hot products of combustion, a circular series of coils communicating 55 with the receptacle, said coils being arranged in pairs, the coils of each pair interfitting, a central coil communicating with the receptacle and surrounded by said circular series of coils, all of the coils overhanging the space for direct contact with the hot products of combustion flowing through the space.

4. A fluid heater including a casing, a fluid receptacle in the upper portion thereof and having vent openings therethrough for products of combustion, a ring-like fluid receptacle in the lower portion of the casing, a circular series of coils interposed between and communicating with the receptacles, 70 said coils being arranged in pairs, the coils of each pair interfitting, and a coil interposed between the receptacles and surrounded by said circular series of coils, all of said coils overhanging the space surrounded by the ring-like receptacle and all of the coils communicating with both of the receptacles. 75

In testimony that I claim the foregoing as my own, I have hereto affixed my signature in the presence of two witnesses.

ADOLF BELER.
